ROBERT A. JOHNSON, OF LONGMEADOW, AND EARLE M. CHASE, OF SPRINGFIELD, MASSACHUSETTS, ASSIGNEES TO PORTER-MCLEOD MACHINE TOOL CO., OF HATFIELD, MASSACHUSETTS, A CORPORATION OF MASSACHUSETTS

ROLL TURNING MACHINE

Application filed May 29, 1928. Serial No. 281,500.

Our invention relates to improvements in machines for turning and dressing hollow cylindrical objects, and more particularly to the means or mechanisms for centering and holding such objects while being turned or dressed, and releasing the same.

Textile-printing rolls require turning down and dressing off, after each design on such a roll has been used to the extent required, and they vary greatly in length, and have tapered bores, openings, or passages therethrough that vary to a considerable extent in size in different rolls, all of which makes it difficult to mount, center, and properly and securely hold in place rolls of this character while being turned and dressed, in turning machines equipped with ordinary types of tail-stocks and chucks. The primary object of our invention is, therefore, to provide a turning machine with adequate and efficient means and mechanism for holding and releasing textile-printing rolls, and other rolls of a more or less similar character, regardless of their lengths and of the sizes of their bores, within predetermined limits.

Another object is to provide, in a machine of this character, mechanism in the tail-stock whereby the holding means for the work are advanced by a quick initial movement and a slow but forceful final movement, and said means are retracted by a slow but forceful initial movement and a quick final movement of said means, to the end that textile-printing rolls, or other hollow cylindrical objects, of different lengths may be expeditiously handled to advantage.

A further object is to provide the machine with chucks, each of which is capable of a wide range of expansion, whereby it is capable of engaging and releasing textile-printing rolls, or other hollow cylindrical objects, having a great variety of different sizes of bores, even when such sizes vary greatly.

These chucks are self-engaging and self-releasing and capable of exerting a great amount of force, under the impetus of the forceful final adjustment of the tail-stock mechanism, with the result that the work mounted on said chucks is not only properly

centered, but is so firmly held as to preclude any possibility of slipping.

Other objects and advantages will appear in the course of the following description.

We attain the objects and secure the advantages of our invention by the means and mechanism illustrated in the accompanying drawings, in which—

Figure 1 is a front elevation of a roll turning machine which embodies a practical form of our invention, parts being in section and broken away; Fig. 2, an enlarged, rear elevation of the tail-stock of said machine, and of the parts and members carried thereby, a portion of said tail-stock being broken away to disclose certain of the mechanism therein; Fig. 3, an enlarged, front elevation and partial section of said tail-stock and its mechanism; Fig. 4, a vertical section through the tail-stock and its mechanism, taken on lines 4—4, looking in the direction of the associated arrow, in Fig. 2; Fig. 5, a vertical section through a portion of the tail-stock, taken on lines 5—5, looking in the direction of the associated arrow, in Fig. 2; Fig. 6, a sectional detail on lines 6—6, looking in the direction of the associated arrow, in Fig. 2; Fig. 7, a side elevation, on a still larger scale, of one of the chucks; Fig. 8, a front or inner end elevation of said chuck; Fig. 9, a longitudinal section through the chuck, taken on lines 9—9, looking in the direction of the associated arrow, in Fig. 8; Fig. 10, a front end elevation of the body of the chuck, and, Fig. 11, a sectional detail on lines 11—11, looking in the direction of the associated arrow, in Fig. 8.

Similar reference characters designate similar parts throughout the several views.

Our invention is embodied in a turning machine the old parts of which will first be briefly described.

Mounted at the ends on two bases 1 is a bed 2, and mounted on said bed at and adjacent to the ends thereof is a head-stock 3 and a tail-stock 7. The tail-stock 7 is an element in the present invention, and will subsequently be described in detail, although its relationship to the bed 2 is substantially like that of any other tail-stock.

A carriage 8 is mounted to slide on the bed 2 between the head-stock 3 and the tail-stock 7, and on said carriage is a slide 10 for an adjustable turning- or dressing-tool carrier or holder 12. An apron 13 depends from the 5 forward edge of the carriage 8, and there appear in front of said apron a hand-wheel 14 for engaging and releasing the carriage 8 with and from a feed-rod 15, and a hand-wheel 16 for engaging and releasing said carriage with and from a rack 17, said feed-rod being journaled in bearings on the front of the bed 2, and said rack being attached to said bed above said feed-rod.

10 A driving shaft 18 is journaled in the head-stock 3, and is driven by a cone-pulley 19 mounted on and secured to said shaft, which cone-pulley in turn is driven by a belt 20. The feed-rod 15 is driven from the shaft 18 by means of a gear 21 mounted on and secured to said shaft, a shaft 22 journaled in bearings in the head-stock 3, a gear 23 mounted on and secured to said last-named shaft, and a chain of gears generally indicated by 15 the numeral 24.

These parts and members being old and well known, the operation of the same will be understood without further explanation.

10 The top of the tail-stock 7 forms a horizontal bearing 25 the axial center of which is in line with the axis of the shaft 18, and slidably arranged in said bearing is a sleeve 26. Journaled in Timken bearings 27—27 adjacent to opposite ends of the sleeve 26 is a spindle 28. The forward terminal of the spindle 28 is enlarged and consists in part of an externally screw-threaded portion 29. In this enlarged part or head of the spindle 28 is an annular groove 30 to receive a felt ring 31. The rear terminal of the spindle 28 is screw 15 threaded, as represented at 32, and two nuts 33 and 34, the latter being behind the former, are screwed onto said terminal. The nut 33 has an annular groove 35 therein to receive a felt ring 36. Thus the parts of the Timken bearing 27 which are on the spindle 28 are held in engagement with the parts of said bearings which are in engagement with the sleeve 26, and oil in said sleeve is prevented 20 from oozing out at the ends thereof.

There is a screw-threaded part (not shown) at the inner or forward terminal of the shaft 18, which part is similar to the threaded part 29 of the head at the inner terminal of the 25 spindle 28.

Secured to the bottom of the sleeve 26, extending longitudinally thereof and in the central, vertical plane of said sleeve, is a rack 37. Intermeshing with the rack 37 is a pinion 38. This pinion is a part of a transverse sleeve 39 which extends through a passage 40 in the tail-stock 7. A bearing plug 41, for the sleeve 39 at the front end, is tapped into the forward end of the passage 40. The 30 passage 40 behind opens into a chamber 42

the back side of which is closed by means of a plate 43 secured to the back side of the tail-stock 7. The plate 43 is provided on the inner side with a bearing hub 44, the axis of which hub is in line with the axis of the 70 sleeve 39. Mounted on and secured to a portion of the sleeve 39 that extends forwardly beyond the plug 41 is a hand-wheel 45, and loosely mounted on the rear terminal of said sleeve, which terminal is in the chamber 42, 75 is a worm-wheel 46.

80 A spindle 47 is partially journaled in the sleeve 39, and extends beyond both ends of said sleeve. Mounted on and secured to the forward end of the spindle 47 is a hand-wheel 48. The rear terminal of the spindle 47 is externally screw threaded, as represented at 49. Journaled in the bearing hub 44, and extending into the chamber 42, is a short sleeve 50 into which the screw-threaded terminal 49 of the spindle 47 extends and with which it engages. A lock screw 51 is introduced into the sleeve 50 from the outer end, and secures said sleeve to the spindle 47. The hand-wheel 48 is against the front end of the sleeve 39, and holds the spindle 47 against endwise movement rearwardly, while other parts and members, presently to be described, hold said spindle against endwise movement 90 forwardly.

95 The back side of the worm-wheel 46 is dished and tapered to form a female member 52 of a friction clutch. A male member 53 of the aforesaid clutch is mounted on and in threaded engagement with the screw-threaded part 49 of the spindle 47, and is prevented from rotating independently of the sleeve 39 by means of two pins 54 which are set in said member on opposite sides of the spindle 47, and extend forwardly or inwardly from said member into passages 55—55 in said sleeve. A washer 56 is mounted on the spindle 47 between the rear end of the sleeve 39 and an adjacent part of the worm-wheel 46, in front of the washer, and a portion of the inner side of the clutch member 53, behind the washer. The pins 54 pass through the washer 56. There is a flange 57 on the spindle 47 behind the washer 56.

100 When the spindle 47 is rotated, it carries 115 with it the sleeve 50, and, due to the screw-threaded engagement between the clutch member 53 and the threaded terminal 49 of said spindle, said clutch member is actuated into and out of engagement with the clutch member 52, according to the direction in which the spindle is rotated, the pins 54 moving in and out in the passages 55, said passages being of sufficient length for this purpose. It follows, therefore, that, when the hand-wheel 48 is rotated in one direction, the clutch member 53 is caused to engage the clutch member 52. Now, if the worm-wheel 120 125 46 be rotated, the clutch member 53 is rotated with said worm-wheel, and said clutch 130

member carries with it, not only the spindle 47, but the sleeve 39 through the medium of the pins 54, the sleeve 26 is caused to be actuated through the medium of the pinion 38 and the rack 37. Upon rotating the hand-wheel 48 in the opposite direction, the screw-threaded part 49 of the spindle 47 causes the clutch member 53 to be actuated rearwardly out of engagement with the clutch member 52, leaving the sleeve 39 free to be rotated by means of the hand-wheel 45. Then the sleeve 26 can be actuated by means of the hand-wheel 45, through the medium of the pinion 38 and rack 37, as before.

15 A key 58 may be employed to prevent the sleeve 26 from rotating.

In the front side of the bearing 25, adjacent to the inner end thereof, is a vertical passage 59 into which opens the bore in said bearing for the sleeve 26. In the passage 59 are upper and under pinch blocks 60 and 61, respectively, which engage the portion of the sleeve 26 that is in the passage 59, above and below the horizontal, plane of said sleeve. 20 There are vertical openings through the blocks 60 and 61, the opening in the lower block being screw threaded, and a rod 62, which is screw-threaded at its lower terminal, is passed down through the upper block into the lower block. Mounted on and secured to the upper terminal of the rod 62, which terminal is above the block 60, is a handle 63.

Upon grasping the handle 63 and partially 35 rotating the same in one direction, the blocks 60 and 61 are caused to approach each other and forced into tight and binding contact with the sleeve 26, thus holding said sleeve against longitudinal movement. This is due 40 to the fact that the hub of the handle 63 bears on top of the block 60, and the lower terminal of the rod 62 is in threaded engagement with the block 61. Upon partially rotating the handle 63 in the opposite direction, the 45 blocks 60 and 61 are caused to separate, or at least to relax their grip on the sleeve 26, thus permitting said sleeve to be moved in either direction.

In the tail-stock 7, behind the bearing 25, 50 and intermediate of the ends of said tail-stock, is a vertical passage 64. A spindle 65 is journaled at the lower end in the bottom of the passage 64, and at the upper terminal in a bearing plug 66 tapped into the upper 55 end of the passage 64. The spindle 65 extends above the plug 66, and mounted on and secured to the upper end thereof is a hand-wheel 67. The spindle 65 is shouldered, as at 68, below the plug 66, and this shoulder 60 and the hand-wheel 67 above said plug hold the spindle 65 against endwise movement. The spindle 65 also has a shoulder 69, below the shoulder 68, and a screw-threaded part 70 to receive a nut 71, and mounted on and secured to said spindle, between the lower

shoulder and said nut is a worm 72. The worm 72 intermeshes with the worm-wheel 46 on the side of said worm-wheel that is adjacent to the outer or rear end of the tail-stock 7.

If, now, while the worm-wheel 46 is engaged by the clutch member 53, the spindle 65 be rotated by means of the hand-wheel 67, the worm 72, rotating with said spindle, actuates the worm-wheel 46, with the result 75 that the sleeve 26 is actuated through the medium of intervening parts and members, as previously explained.

The motion imparted to the sleeve 26, when the hand-wheel 67 is rotated, is very forceful, 80 owing to the presence of the intermeshing worm and worm-wheel, but correspondingly slow, while the movement imparted to said sleeve, when the hand-wheel 45 is rotated, is relatively fast but has much less force be- 85 hind it.

From the foregoing it is seen that a quick, initial, inward movement of the sleeve 26 and consequently of the spindle 28, followed by a slow but forceful final movement, said 90 spindle, and slow but forceful, initial outward movement followed by a quick though less forceful, final movement, may be obtained. Movements of this character are essential in engaging and releasing the work, 95 as will hereinafter be more fully set forth.

Mounted on the screw-threaded part 29 of the head of the spindle 28 is an expanding chuck, and a similar chuck is similarly mounted on the inner end of the shaft 18. Each of 100 these chucks is described as follows:

A body 73 is internally screw threaded adjacent to the rear end, as represented at 74, to receive the screw-threaded part 29, and has therein a central bore 75 which opens through the front end of said body to receive a stem 76 that extends from the back side of a circular nose-piece 77. The back face is of greater diameter than the front face of the nose-piece 77, and the annular side of said 105 nose-piece tapers or curves from said back inwardly toward the axial center of the nose-piece. A taper pin 78 is employed to retain the nose-piece 77 in place against the inner end of the body 73, said pin passing through suitable lateral openings in said body and the spindle 76, as clearly shown in Fig. 11.

The greater portion of the body 73 is tapered or conical, but at the rear end said body is cylindrical, and the tapped opening 110 (74) is in the cylindrical part.

Each of these chucks is equipped with four work engaging elements, but there may be more or less than that number.

Each body 73 has therein, mainly in the conical portion thereof, four slots 79, which slots are equi-distant apart, and the same number of grooves 80. The slots 79 open through the side and front end of the body 73, and the grooves 80 open into said slots and 120

through said end. The grooves 80 are in what may be termed the bottoms of the slots 79, and wholly within said tapered portion of the body 73. Each slot 79 is wider than the associated groove 80, and the difference in width is disposed in equal portions on opposite sides of said groove. The slotted parts, of the conical portion of the body 73, form guide ways which incline, from the cylindrical portion of said body, inwardly toward the axis of said body, to the small end of the body where the nose-piece 77 is located. The open ends of the slots 79 and of the grooves 80 are closed by the nose-piece 77. The outer longitudinal edges of each slot 79 are undercut, as at 81—81, to receive a cross-head 82 which forms the inner part of work-gripping jaw 83. The jaw 83 is adapted to slide in one of the slots 79, with the lateral edges of the cross-head 82 on said body in the undercut portions 81 of said slot, and said jaw is stepped to form two angular, work-engaging parts 84 and 85 on the outer longitudinal edge of said jaw. The jaw might be provided with more or less than two of these work-engaging parts or steps. The parts or steps 84 and 85 on the four jaws always project beyond the outer surfaces of the slotted, conical portion of the body 73.

There are four openings in the nose-piece 77, which openings are in line with the four grooves 80. Each opening 86 extends clear through the nose-piece 77 from front to back, and is enlarged at the forward end to receive a head 87 on a pin 88 located in said opening. A pin 89 extends inwardly from each jaw 83 into the groove 80 partially covered by said jaw. A spring 90 has its ends attached to each pair of associated pins 88 and 89. The springs 90 act to draw the jaws 83 toward the nose-piece 77, and, in the absence of the work, into contact with said nose-piece. Inasmuch as the nose-piece covers the open ends of the slots 79, it is in position to receive the front ends of the jaws 83, when said jaws are completely released to the springs 90.

The steps 84 and 85 adapt the jaws 83 to major differences in sizes of bores in the work, the minor differences being taken care of by the movement of said jaws on inclined planes.

If a piece of work, such as that represented at 91 in Fig. 9, be slipped over the nose-piece 77, it encounters the risers of either the steps 85 or the steps 84, unless the work be too large, of course, and forces the jaws 83 rearwardly in the slots 79, against the resiliency of the springs 90, until said jaws bind so tightly against the inside of the opening in the work that further movement is prevented. This binding contact is made to become sufficient to cause the left-hand chuck to revolve the work, and the latter to revolve the right-hand chuck.

Upon applying force in the direction to withdraw the work from the jaws, or the

jaws from the work, the jaws immediately move towards the nose-piece 77 and thus release their hold on the work, when complete separation is accomplished without difficulty.

A good engagement between the work and the jaws is possible even when all of the jaws are not forced away from the nose-piece 77, as would be the case if the diameter of the work 91 were equal to the distance between one step 85 and the diametrically opposite step 84.

In practice, assuming that the sleeve 26 be in its retracted position, as shown in Fig. 3, that the clutch member 53 is out of engagement with the clutch member 52, and that the pinch blocks 60 and 61 are out of binding engagement with said sleeve, a piece of work, such as a textile-printing roll for example, is mounted at one end on the left-hand chuck, and the hand-wheel 45 is rotated, in the direction to cause the sleeve 26 to be advanced, until the right-hand chuck enters the bore in said roll. The roll or work engages at each end whatever set of steps (84—85) is adapted to receive it, and the continued rotation of the hand-wheel 45 forces the right-hand chuck farther and farther into the work and said work farther and farther onto the left-hand chuck until the frictional resistance between the chucks and the work prevents further rotation of said hand-wheel. Next the hand-wheel 48 is rotated in the direction to cause the clutch member 53 to engage the clutch member 52, when the hand-wheel 67 is rotated in the direction to cause the sleeve 26 to be forced still farther forwardly, with the result that the two chucks are driven very tightly and securely into the work. By the time the engagement between the chucks and the roll is so tight that further movement of the hand-wheel 67 is prohibited, the work is firmly and securely centered and supported by said chucks, and the frictional engagement between the parts is so great that the work can be driven by the left-hand chuck and in turn can drive or rotate the right-hand chuck, with the spindle 28, during the turning and dressing operations on the work. First, however, it is necessary to tighten the blocks 60 and 61 to hold the sleeve 26 against further movement.

The shaft 18 is then set in motion and whatever operations required are performed on the roll or work held by and between the two chucks, said work being driven by the left-hand chuck, as previously stated.

At the end of the turning and dressing operations, the shaft 18 is stopped, the blocks 60 and 61 are loosened to release the sleeve 26, and the hand-wheel 67 is rotated in the direction to cause said sleeve to be retracted, and thus draw the right-hand chuck out of the work far enough to loosen the same. Then the clutch member 53 is disengaged from the clutch member 52, and the right-hand chuck is withdrawn entirely from the work by

70

75

80

85

90

95

100

105

110

115

120

125

130

means of the hand-wheel 45, which latter is rotated in the direction to cause the sleeve 26 to be further retracted. Finally the work is withdrawn from the left-hand chuck.

5 If it were not for the quick action afforded by the mechanism operated by the hand-wheel 45, it would take too long to engage and disengage the chucks with and from the work, and, without the forceful action of which the 10 mechanism operated by the hand-wheel 67 is capable, said chucks could not be engaged sufficiently tightly with the work. In one case there would be force at the expense of speed, and in the other case speed at the expense of force, and both in suitable proportions are necessary.

More or less change in the shape, size, construction, and arrangement of some or all of the parts of this machine, in addition to those 20 to which attention has hereinbefore been called, may be made, without departing from the spirit of our invention, or exceeding the scope of what is claimed.

We claim:

25 1. A tail stock structure comprising in combination, a body having a spindle reciprocable therein, a rack on said spindle, an operating sleeve rotatable in the body having a pinion meshing with said rack, a 30 hand wheel on an outer end of said sleeve at a side of said body, an operating shaft rotatable in said body having a hand wheel at another side of said body, a worm on said shaft, a worm gear rotatable on an inner end 35 of said sleeve having a clutch face, a rod rotatable in said sleeve having a hand wheel at its outer end adjacent said first-named hand wheel, a clutch member associated with an inner end of said sleeve and rod for engaging 40 the clutch face of the worm gear, a member reciprocable in a part fixed to said body for actuating said clutch member and means associated with said rod and member whereby the latter is actuated by rotation of the 45 former.

2. A tail stock structure comprising in combination, a body, a spindle reciprocable therein on a horizontal axis, a rack on said spindle, a sleeve rotatable in said body on a 50 horizontal axis disposed transversely to that of said spindle, a rod rotatable in said sleeve, hand wheels at the outer ends of said sleeve and rod, a shaft rotatable in said body on an axis transverse to that of said sleeve and spindle, a gear on said sleeve meshing with said rack, a worm gear rotatable on the inner end of said sleeve having a clutch face, a worm on said shaft meshing with said gear, a 55 clutch member slid able and non-rotatable on the inner end of said sleeve, a member movable on the inner end of said rod for actuating said member and means associated with said end and member whereby the latter is actuated by rotations of the former.

65 3. A tail stock structure comprising in

combination, a body, having a spindle reciprocable therein and provided with horizontal and vertical bores at adjacent sides of said spindle terminating in a chamber in a side of said body, a plate closing said chamber, a 70 sleeve rotatable in said horizontal bore carrying a pinion meshing with said rack, a rod rotatable in said sleeve, hand wheels at the outer ends of said sleeve and rod, a shaft rotatable in said vertical bore having a hand 75 wheel on its outer end, a worm gear rotatable on the inner end of said sleeve in said chamber provided with a clutch face, a worm engaging with said gear on the inner end of said shaft, a clutch member slid able and non-rotatable on the inner end of said sleeve, a 80 member slid able and non-rotatable in said plate and an inner end of said rod being in screw threaded engagement with said member whereby the member is reciprocated by 85 rotation of the rod to move the clutch member into engagement with the clutch face of the gear.
